UNITED STATES PATENT OFFICE.

FRANKLIN C. HOCKENSMITH, OF PITTSBURG, PENNSYLVANIA, ASSIGNOR
TO HOCKENSMITH WHEEL & MINE CAR COMPANY, OF PENNS STATION,
PENNSYLVANIA, A CORPORATION OF PENNSYLVANIA.

MINE-CAR.

No. 852,879.

Specification of Letters Patent.

Patented May 7, 1907.

Application filed February 14, 1907. Serial No. 357,315.

To all whom it may concern:

Be it known that I, FRANKLIN C. HOCKENSMITH, a resident of Pittsburgh, in the county of Allegheny and State of Pennsylvania, have invented certain new and useful Improvements in Mine-Cars, of which the following is a specification.

The object of this invention is to provide means for strengthening and making more permanent the connection between the body of a car—particularly a mine car—and the axle-confining members or mountings. It is the universal practice to secure these mountings to the underside of the car by bolts extending through the car bottom. These mountings consist of rough castings, and as the openings therein for the securing bolts are simply cored and not machined, the connection with the bottom, while at first comparatively tight owing to the pressure or friction hold of one part upon the other, soon loosens or gives more or less under the rough usage and excessive strain to which mine cars are subjected, and when once loosened the parts wear very rapidly. Furthermore, this loosening of the axle-confining members disturbs the alinement of the axles and the wheels do not run true, thus still further subjecting the car to destructive wear. By reinforcing said members as herein proposed, they are rigidly and permanently held, there being no appreciable loosening, and much wear heretofore considered unavoidable is prevented.

In the accompanying drawings, Figure 1 is a bottom plan view of a portion of a mine car with the improvements applied thereto, and Fig. 2 is a side view of the same, partly in section taken on line 2—2 of Fig. 1. Fig. 3 is a detail view of one of the axle mountings. Fig. 4 is a similar view of a portion of one of the bottom reinforcements.

Referring to the drawings, 2 designates the bottom of the car body, and 3 are the axle-confining members or mountings secured to the under side thereof. The axles 4 may either turn on these members or be held fixed, and wheels 5 may turn on or with the axles, as desired.

Each of members 3 has its upper face formed with depression 6, which extends from side to side thereof in direction parallel

with the axis of axle-confining cavity 7. Portions 8 of the top surface form the opposite side walls of depression 6, and bear upwardly against the car bottom, while thimbles 9, cast integral with body 3, and projecting from faces 8, extend into counter-sunk portions of the bolt passages formed through bottom 2. 10 are the securing bolts extending through said thimbles and through body 3 and the car bottom.

Extending transversely across the under side of bottom 2 are the reinforcing plates or bars 11, the ends of which are entered in depressions 6 of the opposite axle mountings 3. Projecting upward from the bottom of depression 6 is a boss 12, preferably circular in shape, and the end of bar 11 is formed with an opening 13 to embrace the boss. The boss and the bar-opening are much larger than bolts 10, and afford a much greater holding area than is obtainable from one bolt. With the bar and the axle mounting thus interlocked by means of depression 6 and boss 12, the connection is made very secure and permanent, the parts being so united as to practically preclude displacement through wear.

The axle mountings are formed of rough castings and hence there is no accurate fitting of bolts 10 therein, such as is secured by machining.

Cars of this character are produced at such cost as to preclude the expensive machine work necessary for accurate fitting, hence the advantage in so casting the mountings that they are securely held when in place on the car body.

I claim:

1. The combination of a car body; an axle-confining member at the under side of the body and formed with a top depression having opposite side walls, and a reinforcing member for the car body having its end entered in the depression between said walls.

2. The combination of a car body, axle-confining members secured at opposite sides of the bottom thereof, said members alining with each other and each formed with a top depression having opposite side walls, and a transverse reinforcement for the car body having its ends entered between the side walls of said depressions.

3. The combination of a car body, an axle-confining member at the under side of the body, and a reinforcing member for the car body, said member and the axle-confining member being formed with interlocking parts.

4. The combination of a car body, an axle-confining member at the under side of the body, a reinforcement for the car bottom, and an interlocking connection between the reinforcement and the upper side of the axle-confining member.

5. The combination of a car body, an axle-confining member at the under side thereof, a boss projecting from the upper side of the said member, and a reinforcement for the car

bottom formed with an opening to embrace the boss.

6. The combination of a car body, axle-confining members at opposite sides thereof and formed each with a top depression, a boss projecting into each depression, and a transverse reinforcing bar for the car bottom having its ends entered in said depressions and formed to interlock with the bosses. ²⁵

In testimony whereof I affix my signature in presence of two witnesses.

FRANKLIN C. HOCKENSMITH.
